UNITED STATES PATENT OFFICE.

KURT POTTHOFF, OF BROOKLYN, NEW YORK.

COMBINED PEN-WIPER AND INK-BOTTLE SUPPORT.

1,280,541.

Specification of Letters Patent.

Patented Oct. 1, 1918.

Application filed November 10, 1917. Serial No. 201,254.

To all whom it may concern:

Be it known that I, KURT POTTHOFF, a citizen of the United States, residing in Brooklyn, N. Y., in the county of Kings and

5 State of New York, have invented certain new and useful Improvements in Combined Pen - Wiper and Ink - Bottle Supports, of which the following is a specification.

The object of my invention is to provide 10 a combined pen-wiper and ink-bottle support, which may be quickly secured to and removed from ink-bottles of all kinds; but especially adapted for use with bottles used for drafting inks, and which will serve the 15 double purpose of a pen-wiper and an auxiliary support for the bottle preventing spilling of the ink therefrom.

My said invention is disclosed described and claimed in the following specification of 20 which the accompanying drawing forms a part, wherein Figure 1, is a view in elevation of a draftsman's ink-bottle of the ordinary form provided with my improved combined pen-wiper and bottle support; and Fig. 2, 25 is a top-plan view thereof.

Fig. 3, is a partial side view similar to that shown in Fig. 1 of a modified form of 30 my improved combined pen-wiper and bottle support, as applied to a drafting ink-bottle of the form shown in Fig. 1.

Referring to the drawing:—

The reference letter A designates an ink-bottle, as herein shown being one of those ordinarily used for holding draftsman's 35 inks.

Upon the neck A' of this is superposed resiliently, an annular-combined pen-wiping and bottle steadyng disk B, secured to the neck thereof in any desired manner composed 40 of a plurality of foliated superposed ink absorbing leaves of any suitable material.

Such disk is made up of a plurality of layers or plies C of suitable ink-absorbing 45 fabric, such as soft woven absorbent cotton cloth cut into the form of a circular disk having the central securing orifice D, of just sufficient diameter to snugly and resiliently to clasp the neck A' of the bottle 50 A, the construction and arrangement being such that when in position on the bottle-neck, the peripheral edge of the disk will drop down upon the supporting table surface E, as indicated in dotted lines in Fig. 1, 55 so as to form a broad annular supporting base E' preventing accidental overturning

of the bottle; or in some cases may have the plies of fabric of such stiffness and so secured upon the bottle neck, that the same will normally extend horizontally therefrom, as indicated in full lines in Fig. 1; in which case, the disk will only be in contact with the desk or table-top at one point as indicated at E', when accidentally or purposely tilted as indicated by the dotted lines 60 in Fig. 1.

In the form of construction shown in Fig. 3, the several plies of the disk are secured together adjacent to the central securing orifice D, by one or more annular lines of 70 stitches F, while the portion of the disk from said stitches to the edges is left free. The orifice D is of considerably less diameter than the bottle-neck A', so that when forced down over the same it will be held thereon in the 75 downwardly and outwardly peripherally inclined position indicated in the drawing. In the form of construction shown in Fig. 1, the securing orifice D, is provided with an elastic annular securing-ring G, of 80 U shaped form in cross-section, secured to the disk by cementation, vulcanization, or stitches (as at F of Fig. 3) or both; which ring G is usually and preferably of highly elastic Pará rubber, but may consist merely 85 of an impregnation of rubber or other like suitable elastic material forming an annular ring around the central securing-orifice D, vulcanized into the various plies of the 90 fabric.

It is evident that many modifications in the construction and arrangement of the several parts of which my combined bottle support and pen-wiper is composed, other than those set forth herein, may be made 95 without departing from the spirit and scope of my invention; as I do not intend to limit myself strictly to the exact form or forms of construction hereinbefore set forth.

I claim:—

1. A bottle support comprising, with a bottle and a plane surface for resting the bottle-base thereon, an annular disk composed of superposed leaves of flexible material made slightly rigid through superposition of the leaves, means for securing the leaves together adjacent to the bottle neck in superposed relation, the remaining portion of said leaves being free and in superposed relation, and annular means for resiliently engaging the bottle neck to secure said disk thereto; the peripheral edge of the 100

105

110

disk being engageable with said plane surface to prevent overturning of the bottle.

2. A bottle support comprising, with a bottle and a plane surface for resting the 5 bottle-base thereon, an annular disk composed of superposed leaves of flexible ink absorbing material made slightly rigid through super-position of the leaves, means for securing the leaves together adjacent to the 10 bottle neck in superposed relation, the remaining portion of said leaves being free and in superposed relation, and annular means for resiliently engaging the bottle neck to secure said disk thereto; the peripheral edge of the disk being engageable with 15 said plane surface to prevent overturning of the bottle.

3. A bottle support comprising an annular-disk having a central orifice fitting the 20 bottle-neck, and being comprised of a plurality of foliated superposed absorbent leaves.

4. A bottle support comprising an annular-disk having a central orifice fitting the 25 bottle-neck, and being comprised of a plurality of foliated superposed absorbent leaves, unsecured together except adjacent to the central securing orifice.

5. A bottle support comprising an annular-disk having a central orifice fitting the 30 bottle-neck, and being comprised of a plurality of foliated laminated superposed absorbent leaves annularly secured together

adjacent to the central securing orifice and unsecured at the edges, and an elastic soft 35 rubber securing-ring of substantially U shaped form in cross-section secured in the central orifice of the disk, and overlapping the same at top and bottom.

6. The combination with a bottle, of a 40 flexible absorbent disk-like member having a central orifice formed in and through the same provided with an elastic peripheral securing-ring portion adapted to be slipped upon the bottle-neck so as to tightly engage 45 the same, the edges of which disk-like member when the bottle is tilted will by contact with the table or other support prevent complete overturning of the bottle and consequent spilling of the contents. 50

7. The combination with a bottle, of a 55 flexible absorbent disk-like member having a central orifice formed in and through the same vulcanized into the fabric of the disk adapted to be slipped upon the bottle-neck so as to tightly engage the same, the edges of which disk-like member when the bottle is tilted will by contact with the table or other support prevent complete overturning of the bottle and consequent spilling of the 60 contents.

KURT POTTHOFF.
